UNITED STATES PATENT OFFICE.

JOSEPH LEON GOBEILLE, OF CLEVELAND, OHIO, ASSIGNOR TO MYERS, OSBORN & CO., OF SAME PLACE.

DESIGN FOR A COOKING-STOVE.

SPECIFICATION forming part of Design No. 15,740, dated January 20, 1885.

Application filed November 19, 1884. Term of patent 3½ years.

To all whom it may concern:

Be it known that I, JOSEPH L. GOBEILLE, a citizen of the United States, residing at Cleveland, in the county of Cuyahoga and State of Ohio, have invented and produced a new and original Design for Cooking-Stoves, of which the following is a specification, reference being had to the accompanying drawing, forming part thereof.

10 The figure is a perspective of the stove.

The door A of the stove-oven, of shape as appears in the drawing, and hinged with the decorated hinge B, is centrally embellished by the prominent star C, pictorially projecting 15 from the background c, and having the leaf-like figures c' reaching between its several points. On each side of the said star, and obliquely across the face of the door lie, respectively, the flowered strips D and D'. The 20 four corners or cornering portions of the said door have figures of arboreal branches, respectively lettered d, d', d'', and d''. The door E of the fire-box is also obliquely crossed by the flowered strip e, lying across an arboreal 25 branch, one of whose sections—viz., e'—lies above said strip, and the other of whose sections—viz., e''—lies below the said strip. Door F of the heating-closet has a central figure of a circle or disk, f, lying over a bifurcated 30 stem, one of whose sections—viz., f'—lies obliquely below the center of said disk, while the other two branching portions—viz., f'' and f'''—lie obliquely above the center of said disk; also, said door is further ornamented by the 35 flower-sprigs f' and f''. The exterior side surface of the reservoir G is decorated by the two vertical columns g g', located near its edges, said columns respectively embellished by the figures g'', and flanked, respectively, on one 40 side by the vertical scroll g''. Said door has also the window-like frame g', having the flowered device g'' extending vertically through its center. The stove-legs H have severally upon them the figure of an open sunflower, h, 45 bordered by the spreading leaves h'. The scalloped curtain I, reaching along the bot-

tom of the side of the stove from leg to leg, has the circular figures i in the upper line, and the radiated figures i' in the lower line. Said curtain also has both its ends decorated 50 with the scroll i'', and the small star i' has arboreal sprig k. Under the bottom horizontal line of oven-door A projects the lattice-faced supporting-shelf M. The exterior end of the ash-pit N has the star n, with a surrounding 55 net-work, n', formed between its points.

What I claim is—

1. A design for a cooking-stove, consisting of the ornamentations, severally and in aggregation, on the doors, water-chest, hearth-lid, legs, and other portions, as herein set forth, described, and shown.

2. The design for the oven-door A, consisting of the central star, C, background c, leaf-like figures c', oblique strips D and D', and 65 the arboreal branches d, d', d'', and d''', substantially as set forth.

3. The design for the door E of the fire-box, consisting of the oblique strip e, lying across an arboreal branch, one of whose sections— 70 viz., e'—is located above said strip, and the other of whose branches—viz., e''—lies below the said strip, substantially as set forth.

4. The design for the heating-closet door F, consisting of the center disk, f, lying over a 75 bifurcated stem that has one of its sections—viz., f'—below the center of said disk, and its other two branching portions—viz., f'' and f'''—lying obliquely above the said center of said disk, substantially as set forth. 80

5. The design for the exterior faces of the ends of the ash-pit N, consisting of the star n, having an interlaced net-work, n', formed between its several points, and stretching from point to point, substantially as set forth. 85

In testimony that I claim the foregoing to be my invention I have hereunto set my hand this 13th day of November, A. D. 1884.

JOSEPH LEON GOBEILLE.
